INDIVIDUAL SHINGLE

Filed July 29, 1925

Inventor:

Henry R. French,

By George Bruce Umbry May

Attys.

UNITED STATES PATENT OFFICE

HENRY R. FRENCH, OF RUTHERFORD, NEW JERSEY, ASSIGNOR, BY MESNE ASSIGNMENTS, TO THE PATENT AND LICENSING CORPORATION, OF BOSTON, MASSACHUSETTS, A CORPORATION OF MASSACHUSETTS

INDIVIDUAL SHINGLE

Application filed July 29, 1925. Serial No. 46,701.

This invention relates to flexible asphalt roofing shingles serving as protecting or covering elements for a roof or side wall of a building, and adapted to be laid thereon in 5 overlapping courses.

Such shingles are usually cut from a sheet comprising a foundation of fibrous material saturated or impregnated with asphalt of low melting point and coated on either or 10 both its faces with a layer of asphalt of high melting point, in which is partially embedded on its outer or exposed face a surface layer of sand, crushed slate, granite, or equivalent mineral material.

15 The objects of the present invention are chiefly to provide a prepared shingle which will permit a maximum area of roof surface to be covered with a minimum amount of material, which may be laid rapidly and 20 accurately, which will impart a pleasing pattern or effect to the roof surface when laid, and which may be cut from a shingle-forming sheet with a minimum amount of wastage.

25 Briefly stated, these objects are attained in a shingle which is characterized by the fact that, while it is an individual shingle, it possesses the advantage incident to the usual strip shingle simulating a plurality of 30 individual units, namely, its capability of being rapidly laid and of covering a maximum surface. The individual shingle of the present invention is of symmetrical configuration, one prominent or outstanding feature of which is its substantially greater 35 length or elongation relative to its width.

On the accompanying drawing,

40 Figure 1 illustrates a method of cutting shingles embodying the present invention from a sheet.

Figure 2 represents in perspective view a shingle embodying the present invention.

45 Figure 3 represents in plan view a roof surface covered with the shingles shown in Figure 2, and illustrates the method of laying and securing the shingles to the surface.

50 Figure 4 illustrates a method of cutting a modified form of shingle embodying the present invention.

Figure 5 represents in perspective a shingle produced by such cutting.

Figure 6 illustrates a method of laying and securing the shingles of Figure 5 to a roof surface.

55 Referring to the drawings, S represents a sheet of indeterminate length, which comprises a base or foundation of fibrous material saturated with suitable waterproofing material such as asphalt, and coated on its outer or exposed face (or on both faces if desired) with a layer of high melting point asphalt which will not run when exposed to solar heat, in which is partially embedded a 60 surfacing of crushed slate or equivalent material.

65 Between the edges f and f₁ of the sheet, there are made alternately at regularly spaced intervals, by cutting mechanism or by any other suitable instrumentality, a symmetrically reversing or zigzag cut abab, and a similar cut edcd out of phase with the first mentioned cut by a single length, the sections ab and cd alternately converging and diverging, and the reversal taking place at 70 obtuse angles, say of about 150 degrees, indicated as Z. The ends of the sections are joined by short cross-cuts bd and ac, and near the edges f and f₁ of the sheet, respectively, by the slits ce and ae, thus producing 75 shingles of a hexagonal configuration illustrated in Figure 2, and simultaneously therewith at the edges of the sheet a series of incomplete or edge shingles J, which I employ for a purpose hereinafter described. 80 While I have described one method of cutting, any other suitable method may be followed in producing the shingles of the present invention from a shingle-forming sheet.

85 The shingle 1 shown in Figure 2 is of 90 hexagonal configuration, its lower edges lr, pr and upper edges mn, no being of equal length and forming equal obtuse angles Z with each other and with its side edges lm and po, which are of equal and relatively 95 short length. In other words, the shingle is of a symmetrical hexagonal configuration of elongated length, the length being preferably at least twice the width. In actual practice the shingles are preferably 24 inches long 100.

and 8 inches in width, but they may be 36 inches long and correspondingly increased in width.

The shingles 1 are laid in overlapping courses, as indicated in Figure 3, with the edge shingles J, formed in cutting up the shingle-forming sheet, serving as starters. The starters are applied, as to a roof, with their edges ee at the edge of the roof, and are fastened thereto by fasteners as at h. The shingles 1 are then laid in a superposed course, with the points r coinciding with the points e of the starters and the points m and o coinciding with the points d of two adjacent starters. The shingles are fastened to the roof somewhat above and adjacent the points p and l, and the laying is continued, the points r of the shingles of the overlying or superposed courses being made to coincide with the coincident points p and l of the underlying courses, and the points m and o of the overlying courses being made to coincide with the points n of the underlying course, such laying resulting in an alinement 25 of the edges rp and rl of all the courses with the corresponding edges of the superposed and underlying courses, and producing a combination and individual diamond effect or pattern. The shingles may be applied to 30 the roof or other surface rapidly because of their self-aligning characteristics and their elongated length, and produce a pleasing and novel appearance.

In Figure 3 I have illustrated a modified 35 method of cutting, to produce another form of shingle embodying the present invention. In this instance the sheet is cut between its edges alternately at regularly spaced intervals along the wavy, symmetrically reversing 40 or sinusoidal line a'b'a'b', and along a similar line c'd'c'd', out of phase with the first mentioned cut by a wave length c'd'. There are thus formed a series of longitudinal strips 45 consisting alternately of wide and narrow portions. The narrow portions are joined at their points of minimum width by the cross slits b'd' and c'a', producing shingles of the configuration illustrated in Figure 2, and at the edges of the sheet the starters J'.

The shingle 3 produced, shown in Figure 5, comprises, respectively, upper and lower edges m'o' and l'p', having the same wavy or sinusoidal curvature, the curves diverging to a point of maximum distance of separation at the central portion of the shingle, and converging to points of minimum distance of separation at the ends of the shingle, where both upper and lower edges are joined by the parallel, equal length and relatively short 55 side edges m'l' and o'p'. In other words, it is also a shingle of symmetrical configuration, and its dimensions as to length and breadth may be substantially equal to those of the shingles first herein described.

In Figure 6 I have illustrated a method of

applying the shingle shown in Figure 5 to a roof. The starters J' are first applied with the edge e'e' at the edge of the roof, and are fastened thereto slightly above and adjacent the points p' and l' by fasteners indicated at h. The shingles 3 are then laid in a superposed course with the centers of the edges l'p' coinciding with the points e' of the starters, and the points m' and o' coinciding with the center point of the upper or curved edge of the starter, and fasteners are applied above and adjacent the points p' and l', as at h'. The laying is continued and the shingles of the overlying courses are applied so that the center points of the edge l'p' coincide with the coincident points p' and l' of the shingles in the course therebelow, and the points m' and o' coincide with the mid points of the upper edges m'o' of the shingles in the course therebelow. Such laying produces a novel pattern or effect on the roof, consisting of tangential, sinusoidal or wavy lines, the combination effect resembling "chicken wire" in configuration.

While I have employed the relative terms "upper" and "lower" in the specification, it is obvious that this was by the way of convenience in description only, and that since the shingles of this invention are symmetrical, they may be inverted in their application to a roof or other surface.

Before concluding, in order to give a more comprehensive understanding of the present invention and the results achieved thereby, it may be of advantage to supplement the foregoing by a specific instance. For example, assuming the sheet S to be 72 inches in width and the symmetrical hexagonal shingle produced therefrom to be 24 inches in length along its longitudinal median line, 8 inches in width along its transverse median line, and 2 inches in width along its side edges, and following the method of laying illustrated in Figure 3, a 2-inch overlap of the upper edges of the shingle—as indicated by the cross-hatched shingle portion in Figure 2—is obtained and a square (100 square feet of roof surface) is covered by 167 square feet of material. Including the starters, 174 square feet of material is necessary to manufacture one square of the shingles, or in other words $\frac{1}{8}$ of the material goes into the starters as compared with $\frac{7}{8}$ that goes into the shingles. The starters, however, may also be employed as regular strips or hip and ridge strips.

With the shingle illustrated in Figure 3, assuming the same dimensions as those of the hexagonal shingle, the amount of overlap as shown by the cross-hatched portion, and the roof coverage obtainable therefrom, is substantially equal to that of hexagonal form. I desire to have it understood, however, that the dimensions of the shingles and the results obtained in their laying are subject to considerable variation.

Having thus described certain embodiments of this invention, it should be understood to those skilled in the art that these are capable of various changes and modifications 5 without departing from the spirit or scope of this invention as defined by the appended claims.

What I claim is:

1. An elongated individual asphalt shingle, 10 of symmetrical hexagonal configuration, adapted, with others, to be laid in overlapping courses and having pairs of adjoining upper and lower edges forming equal obtuse angles with each other and with a pair of relatively short side edges perpendicular to the longitudinal median line of the shingle.
2. An elongated individual asphalt shingle of symmetrical hexagonal configuration, adapted, with others, to be laid in overlapping courses and having pairs of adjoining upper and lower edges of equal length, forming obtuse angles of about 150 degrees with each other, and forming equal angles with a pair of relatively short side edges.
- 25 3. An individual flat asphalt shingle of symmetrical configuration adapted with others to be laid in overlapping courses, said shingle having relatively short vertical side edges and relatively long upper and lower 30 edges diverging from said side edges to points of maximum separation on the vertical axis of the shingle, the horizontal axis of the shingle being at least twice the length of the vertical axis.
- 35 In testimony whereof I have affixed my signature.

HENRY R. FRENCH.
